UNITED STATES PATENT OFFICE.

CHARLES F. BROWN AND HENRY R. BROWN, OF GREENEVILLE, TENNESSEE.

PIN-HOLDER.

SPECIFICATION forming part of Letters Patent No. 726,252, dated April 28, 1903.

Application filed October 6, 1902. Serial No. 126,190. (No model.)

To all whom it may concern:

Be it known that we, CHARLES F. BROWN and HENRY R. BROWN, residents of Greeneville, in the county of Greene and State of Tennessee, have invented certain new and useful Improvements in Pin-Holders; and we do hereby declare the following to be a full, clear, and exact description of the invention, such as will enable others skilled in the art to which it appertains to make and use the same.

Our invention relates to an improvement in pin-holders, and more particularly to a combined pin-holder, penholder, and paper-weight, the object of the invention being to provide an improved pin-holder in which the pins in their paper can be secured in the holder and a line of pin-heads be exposed to permit the pins to be readily removed without danger of pricking the fingers.

With this object in view the invention consists in certain novel features of construction and combinations and arrangements of parts, as will be more fully hereinafter described, and pointed out in the claims.

In the accompanying drawings, Figure 1 is a perspective view illustrating our improvements. Fig. 2 is a view in cross-section, and Fig. 3 is a view showing the holder open.

Our improved holder comprises two sheet-metal plates 1 and 2, the former bent longitudinally and at an approximately rightangle, forming the bottom and back of the holder. The other plate or cover 2 is hinged to the bottom at its forward edge by means of a pin or wire 3 and is bent longitudinally near its hinged edge, as shown at 4, and projects toward the back, forming a slightly-inclined platform 5, and is again bent longitudinally, as shown at 6, forming a lip 7 against the back and terminating when the holder is closed parallel with the upper edge of the back, clamping a row of pins between the same and back, which latter is provided with a spring-tongue 8 to spring over the cover 2 and hold it in its closed position, and a lug or finger-hold 9 is provided on the back near tongue 8 to facilitate the opening of the cover when desired.

The inclined platform 5 serves as a pen rack or holder, and lugs 10 are bent up from the

platform near its forward edge to prevent the pens from rolling off the holder.

In operation a paper of pins 11 is placed in the holder with one strip or file of pins, the heads of the pins being uppermost, placed 55 against the back. The cover 2 is now closed and locked by spring-tongue 8, leaving the heads of the pins exposed and in position to be grasped and drawn from the paper, and when one row or file of pins has been removed 60 this strip of paper is torn off and another file placed in position as before.

It will be seen that our improvements will also serve as a paper-weight, being conveniently moved, and will be a great convenience 65 upon a desk or table, having the pins always ready for use and precluding possibility of pricking the fingers in removing them.

A great many slight changes might be made in the general form and arrangement 70 of the several parts described without departing from our invention, and hence we do not limit ourselves to the precise construction set forth, but consider ourselves at liberty to make such slight changes and alterations as 75 fairly fall within the spirit and scope of our invention.

Having fully described our invention, what we claim as new, and desire to secure by Letters Patent, is—

1. A pin-holder constructed to receive a paper of pins and having means for holding a row of said pins exposed.

2. A pin-holder comprising two members movable relatively to each other and constituting a receptacle for a paper of pins, the free edges of said members coöperating to hold a row of said pins exposed.

3. A pin-holder comprising two plates hinged together and constituting a receptacle 85 for a paper of pins and means for clamping a row of pins between the free edges of said plates.

4. A pin-holder comprising two bent plates hinged together, each plate having an upwardly-projecting member, the lower members of said plates coöperating to form a receptacle for a paper of pins and the upwardly-projecting members coöperating to hold a row of said pins with their heads exposed.

5. As a new article of manufacture, a pin-holder, comprising two plates hinged together, a spring-tongue on one plate to clamp the other and hold the paper of pins between them exposing the heads of one row of pins.
6. As a new article of manufacture, a pin-holder, comprising one plate bent at right angles, another plate hinged thereto and when folded forming a receptacle for a paper of pins, a spring-tongue on the upper edge of the first-mentioned plate to spring over the edge of the other plate and hold a row of pins in a vertical position with their heads exposed above the upper edges of said plates.
- 15 7. As a new article of manufacture, a pin-holder comprising a plate bent at right angles and supporting a paper of pins against the same, a bent plate hinged to the first-mentioned plate to inclose all but the heads of

one row of pins and lugs on said last-mentioned plate to limit the movement of pens or like articles thereon.

8. As a new article of manufacture, a combined pin-holder, penholder and paper-weight, comprising two plates of sheet metal 25 hinged together and bent to inclose a paper of pins and form an inclined platform to support pens thereon, and lugs on the platform to limit the movement of the pens.

In testimony whereof we have signed this 30th day of January, 1899, in the presence of two subscribing witnesses.

CHARLES F. BROWN.
